UNITED STATES PATENT OFFICE

WALTER C. FELLOWS, OF PHILADELPHIA, PENNSYLVANIA, ASSIGNOR TO C. E. CARVER COMPANY, A CORPORATION OF PENNSYLVANIA

FINGER GUARD FOR PRESSES

Application filed October 2, 1926. Serial No. 139,121.

The object of my invention is to provide an efficient finger guard for stamping or embossing presses and for other machines in which there is employed a reciprocable moving part in the path of the fingers of the operator during the feeding of the paper or material required to be acted upon.

My invention is also to so construct the finger guard that it may be automatically operated during the normal operation of the machine and, at the same time, have provision for putting the guard out of operative position when the machine is at rest, whereby access may be had to the working portions of the machine, the said functioning, however, being preferably so controlled that when the machine is again put into operation, it automatically puts the finger guard also again into proper operation. This capacity of my invention prevents the attendant from putting the finger guard out of use during operation of the press and yet permits its quick displacement when out of operation for purposes of adjustment, test or repair.

My invention also has for a further object the finger guard so constructed that it may be adjusted to suit dies or counter blocks of different sizes whereby, when the die is changed according to the work to be done, the operator of the press may at once readjust the finger guard so that it may perform its function under substantially the same conditions as to safety as formerly.

With these and other objects in view to be performed and secured, my invention consists of certain improvements in finger guards for stamping and embossing presses and for other machines, having the particular features of novelty as fully set forth in the following specification and defined in the claims.

For more fully describing the details of my invention, I have provided drawings forming a part of the specification, in which: Fig. 1 is a front elevation of my improved finger guard as applied to an embossing and stamping press; Fig. 2 is a side view of the same; Fig. 3 is a perspective view showing the special means applied to the plunger for insuring operation of the apparatus; and Fig. 4 is

a plan view of a fragmentary portion of my improved finger guard.

2 represents the die and 3 the die-chuck for holding and moving the die as may be required in stamping and embossing presses. 4 is the vertically reciprocating plunger guided in the main frame or housing 4^a and having at its lower end a suitable counter-block 2^a adapted to cooperate with the die member 2. The work table, extending into close working relation with the die, plunger and working parts of the press or other machine, is shown at T in Figs. 1 and 2, and the special function of my invention to prevent the fingers, while manipulating the paper or other material, becoming pinched or mutilated between the plunger and counter-block on the one part and the die on the other part.

The finger guard is shown at 8 and is formed of a transverse strip of rubber (preferably fabric faced) clamped along its upper portion between a transverse guard bar 9 and front plate 10 by means of rivets or screws 10^a, the construction being such as to provide a yielding guard capable of forcibly pushing the fingers out of the danger zone when the plunger 4 is descending. The finger guard bar 9 is secured at its ends to operating levers 6, 6, hinged or fulcrumed at 7 and extending downward and bent inward toward the die so that the rubber guard lies in an oblique plane to the operative surface of the die. The upper ends of these levers 6, 6, are fulcrumed to normally stationary frames 11, 11, which are horizontally adjustable upon the fixed supporting bracket 5, said bracket being bolted to the guide frame and cap 4^a of the press by cap screws 5^a. The adjustability of the frames 11, 11, is to position the finger guard 8 to or from the plunger to accommodate it- 90

self to dies and counter-blocks of different sizes, as indicated, for example, by the dotted lines below the letters x, x, y, y, and solid lines below the letters z, z, in Fig. 2, the said designations x-x, y-y, and z-z being possible widths of the dies. The adjustment of the frames 11, 11, is secured by having horizontal slots 12 therein and cap screws 13 extending through the slots and screwed into the side portions of the supporting bracket 100

5. The screws 13 act as guides for the frames 11, 11, and also for holding them rigidly to the bracket when adjusted.

A horizontal plate 14 is arranged below each of the frames 11 and said plates are connected to said frames by links 15 and 16, the former as guiding links and the latter as operating links. The forward ends of the horizontal plates 14, 14, are each provided with lateral pins or studs 14^a which engage socket portions 6^a in the respective levers 6, 6. It will now be understood that the links 15 are hinged at their upper ends to the frames 11 by hinge pins 17 and at their bottom ends to the plates 14 by hinge pins 18. Similarly, the operating links 16 are hinged at their upper ends to the respective frames 11, 11, by pins 19 and at their lower ends to the corresponding plates 14, 14, by pins 20. The plates 14, 14, are therefore free to swing horizontally except as controlled in the manner hereinafter explained.

To operate the finger guard, the following instrumentalities are employed. The links 16, 16, are each provided with a roller 22, maintained in working contact with the respective lifting cams 24, 24, which are provided with cam shoulders 26. Two coiled springs 30, 30, each having one end connected with one of the side frames 11, 11, and the other end connected to one of the levers 6, act to swing back the U shaped finger guard frame 6, 9, 6, against the forward ends of the horizontal plates 14, 14, with the result that rollers 22, 22, are yieldingly pressed in contact with the respective lifting cams 24, 24. The cams are in the form of vertical bars guided in vertical grooves 23 in the rear end of the horizontal adjustable frames 11, 11, as shown in Fig. 2, and are retained in said grooves by cap plates 23^a (Fig. 4). The lift cams 24 may be reciprocated vertically by the machine in any suitable manner provided their reciprocations are in timed relation to the operating plunger or other operative part against which the fingers are to be protected. I have shown, however, a simple manner whereby the cams are directly actuated by the plunger itself. I provide horizontal cam actuating bars 27 at each side of the plunger 4 and conveniently shape them to fit upon the drip pan 28 which surrounds the plunger and rigidly secured to it, the bars being fastened to the drip pan by cap screws 29. The rear ends of the bars 27 extend against the sides of the cams between lateral pins 25 projecting from the cams. In this manner, the cams 24 are reciprocated up and down simultaneously with the up and down movements of the plunger 4, and hence in timed relation therewith. As shown in Fig. 2, the finger guard 8 prevents the fingers getting between the die and plunger, but as the plunger continues to rise, the cams 24, 24, will ultimately move the cam shoulders 26,

26, past the rollers 22, 22, and permit the springs 30, 30, to pull the guard backward between the die and plunger and to the position shown in dotted lines in Fig. 2, leaving large clearance for the removal of the next sheet or object as well as the insertion of a new sheet or object. The initial downward movement of the plunger quickly returns the finger guard 8 to the position shown in full lines (Fig. 2) long before it descends to a dangerous zone. The movement of the finger guard is preferably a quick one and timely so that the operator can not avoid its meaning nor resist its action, since its ejecting movement is a positive one, being backed by the action of cams 24. Assuming that by any cause the finger or a tool happened to be under the guard as it descends, the fact that it has a rubber edge will permit the quick release of the finger or tool without injury.

I have before referred to the fact that the guard may be turned up out of operative position for permitting access to the working parts of the machine, but that as soon as the machine functions normally, the guard is automatically moved into protecting position, and I will now describe the means for securing these results. As shown in Fig. 2, the spring 30 holds the lever 6 of the finger guard against the pin 14^a of the plate 14, but the guard may be turned forward and upward about its hinge or fulcrum 7; and as the point of action of the spring 30 is thus changed from below the fulcrum to a point above the same, the effect of the spring is to hold the guard in its upward position. In this position, the guard is entirely out of the way of the operator in changing or adjusting dies and counter-blocks or for other requirements. As it is possible for the press to be operated with the guard in this inoperative position, it is necessary to provide means which will automatically readjust the guard to its operative position. For this purpose, I provide the cam actuating bars 27 with forward extensions 31 which respectively extend laterally over the levers 6, 6, of the finger guard when the guard is raised to inoperative position. When the plunger moves down, it carries the extensions 31 with it and causes them to press upon and force down the levers 6, 6, against the action of the springs 30, 30, until their connection points with the levers descend below the level of the fulcrum points 7, 7, and thereafter the springs quickly force the finger guard down into proper functioning position, this all being done automatically by the action of the machine itself. In this manner, the guard is always in position to properly function when the press or machine is in operation, but may be adjusted into inoperative position when the press or machine is out of operation.

I have described my invention as having

duplicate cams 24 and other operating parts at the right and left sides of the finger guard; and while this application gives very positive action, it will be manifest that where proper 5 rigidity of parts are provided, the guard may be operated by use of one cam 24 and plate 14 only. In this case, one side of the mechanism will be as shown in Fig. 2, while the other side need only provide the adjustable 10 part 11 to which the lever 6 of the guard may be hinged.

Among the more important features of improvement, the following may be pointed out: The finger guard mechanism is adjustable 15 to all sizes of dies and counter-blocks. The movement of the guard and the clearance provided is the same for all sizes of dies and counter-blocks when the plunger is up and the guard is also up and lifted to the under-side of the counter-block. If the springs 30 should break or become disengaged, the finger guard will fall by gravity to a protecting position and thereby issue the same danger warning to the operator. The guard cannot 20 be forcibly pushed inwardly when the plunger is on its downward course and consequently it is not possible for the operator to get his fingers under the plunger at such time. There is nothing in the mechanism to cause the guard to become inoperative and it 25 will continue to function properly until actually worn out. The device is compact and positive and easily applied. No adjustments are required for any purpose except when different sizes of dies and counter-blocks are 30 required. The mechanism is practically noiseless and, therefore, is not disconcerting to the operator. The guard in principle is adapted to be used with a large variety of machines.

40 It will now be apparent that I have devised a novel and useful construction which embodies the features of advantage enumerated as desirable, and while I have in the present instance shown and described the preferred embodiment thereof which has been 45 found in practice to give satisfactory and reliable results, it is to be understood that I do not restrict myself to the details, as the same are susceptible of modification in various particulars without departing from the spirit or scope of the invention.

Having now described my invention, what I claim and desire to secure by Letters Patent is:

55 1. A finger guard of the character described, comprising in combination with a machine to which it is applied a hinged finger guard extending downwardly and adapted 60 to swing backward from in front of the operating parts of the machine to which it is applied to a position between them, a cam arranged at the rear of the operating parts of the machine and operated by one of said 65 parts, a substantially horizontal reciprocable

part positively moved in one direction by the cam and having its forward end in contact with the finger guard to push it from between the operative parts of the machine forward of said parts, and a spring acting 70 upon the finger guard for yieldingly forcing it backward against the reciprocable part and maintaining it in operative relation with the cam.

2. The invention according to claim 1, 75 wherein further, the spring is connected with the finger guard below its hinge axis whereby when the guard is turned upward out of operative position, the connection of the spring therewith will be positioned above the hinge axis to hold the guard in its raised inoperative position, and means operated by the machine are provided for automatically moving the finger guard and the spring into operative positions when the machine is put into 80 normal operation.

3. The invention according to claim 1, 85 wherein further, the spring is connected with the finger guard below its hinge axis whereby when the guard is turned upward out of operative position, the connection of the spring therewith will be positioned above the hinge axis to hold the guard in its raised inoperative position, and means operated by the machine are provided for automatically moving the finger guard and the spring into operative positions when the machine is put into 90 normal operation, said means consisting of an extension moving with an operative part of the machine and projecting laterally over a portion of the hinged finger guard to 95 push it downward against the action of the spring.

4. The invention according to claim 1, 100 wherein further, an adjustable frame is provided to which the finger guard and reciprocable part are hinged and by which the cam is supported, a supporting frame is fixedly secured to the machine, and adjusting means are arranged for connecting the adjustable frame to the supporting frame in different 105 positions of adjustment.

5. The invention according to claim 1, 110 wherein further, lever means are provided between the reciprocable part and the cam whereby the action of the cam upon the finger guard provides an increased movement of the latter.

6. The invention according to claim 1, 115 wherein further, the reciprocable part comprises a horizontal plate hung by parallel links and the cam consists of a vertically reciprocable cam bar having a side cam surface and operating upon one of the links by means of a roller carried thereby.

7. The invention according to claim 1, 120 wherein further, the finger guard comprises a U shaped metallic frame having its lower part provided with a horizontal bar having a pliable rubber strip projecting downward.

8. The invention according to claim 1, wherein further, the reciprocable part is hung in links so as to swing horizontally in one direction under the action of the spring and in the other direction under the action of the cam.

9. The combination with a machine having stamping dies of a finger hinged on a horizontal axis in front of the dies and normally hanging downward but capable of being turned in an upward position above the axis, an operating means for the finger guard arranged at the rear of the dies and operated by the machine simultaneously with the operation of the dies thereof, a mechanical connection between the operating means and the pivoted finger guard when hanging in its downward position, and a spring connecting with the finger guard at a point below its axis whereby the guard is yieldingly pressed against the mechanical connection to insure a backward motion to the guard under the control of the operating means and whereby further the spring holds the guard out of operative connection with the mechanical means when the guard is turned in an upward direction.

In testimony of which invention, I hereunto set my hand.
